BED-COUCH

William F. Schorn, Alexandria, Va.

Application October 26, 1945, Serial No. 624,928

3 Claims. (Cl. 5—136)

(Granted under the act of March 3, 1883, as
amended April 30, 1928; 370 O. G. 757)**1**

The invention described herein, if patented, may be manufactured and used by or for the Government of the United States for governmental purposes without the payment to me of any royalty thereon or therefor.

The present invention relates to a bed-couch particularly of the folding type. It is a primary object to construct a folding bed-couch that may be folded rapidly to a flush position in a vessel wall, bulkhead, or cabinet fixed or portable.

It is an object to provide a construction alternately useful for either a bed or couch.

It is a further object to construct such device with a simple cantilever support requiring no adjustment of the bed element to be stable in both open and closed positions and having no depending legs or braces or suspending brackets, the absence of which eliminates necessity of adjustment, simplifies construction, provides maximum room beneath the bed in the open position, maximum safety to the user when the bed is used on a rolling ship or vehicle, and maximum ease of folding.

In the drawings—

Fig. 1 shows a fragmentary perspective view of the closed cabinet whenever the bed-couch is folded;

Fig. 2 shows a similar perspective of the opened bed-couch set for use as a couch with part of the cabinet walls broken away to show the construction thereof;

Fig. 3 is a side elevation of the bed-couch in folded position partly in section to show arrangement of the folded parts looking in the direction of the arrows on the line 3—3 of Fig. 1;

Fig. 4 is an end view of the opened bed;

Fig. 5 is an enlarged detail of the folding cover as it appears at the upper edge of Fig. 3;

Fig. 6 is an enlarged detail in which the construction of the pivot is shown; and

Fig. 7 is an enlarged detail of a corner section of the bed showing arrangement of the braces and stop to hold the bed stable in open position.

Referring to the drawings in detail, 10 indicates generally a bed-couch cabinet or a recessed wall or bulkhead containing a bed-couch. When a cabinet is used, as shown in closed or folded position of Fig. 1, the cabinet is constructed of ends 11, bottom 12, reinforced at the edges with plates 12' and back 13 and open front closed by the bottom of the bed 14, and a folding shelf top 15. When the cabinet is replaced by a recessed wall, the sides and top are the boundaries of the recess, the top being omitted and the bottom is the floor or deck, the bed construction

2

being otherwise the same and fitted in the wall recess in a manner similar to that shown for the cabinet.

The sides of the cabinet are reinforced or stiffened with suitable bracing such as vertically placed channels, angle or T-irons 16, covered by protective sheathing 17.

The bed 18 is of any suitable construction and as shown may be made of metal frame members 19, bounding the sides and ends, having bottom stiffeners 20 extending from side to side. Interwoven resilient straps 21 are attached to a channel 22 welded or otherwise fastened to the side and end on frame members 19 to form a spring. Fitted within the boundaries of the frame 19, and mounted on the straps 21, is a mattress 23 suitably fixed to the frame against movement when the bed is folded.

The bed is mounted lengthwise of the cabinet upon a pair of pivot members 24, shown in detail in Fig. 6, at the head and foot ends of the bed, respectively. The male portion of the pivot members are secured to an iron stiffener 25 welded or otherwise fastened to the frame interior, and are located off-center, i. e., about two-thirds of the distance from the outer side of the bed, the exact position being fixed by necessity of obtaining correct stability and balance for easy folding as hereinafter explained. The channel 22 is discontinuous in the vicinity of the pivot (not shown) to allow easy access thereto. To rigidly fix the pivot pin, a nut 26 is welded to the angle iron 25 and the angle 25 as well as the frame member 19 are coaxially bored and threaded with the nut 26 to receive a partially threaded case hardened pivot pin 27 having a head 28 and smooth bearing surfaced shank 29 with an intermediate threaded portion 30. Suitable washers 31 may be placed intermediate the bolt head 28 and nut 26 for the firm fastening of the bolt 27. The opposite smooth end of the bolt 29 is mounted for rotation and support in bushings 32 suitably fixed respectively to the ends 11 of the cabinet. These bushings are each provided with a recess 33 coaxially of the bushing to receive a coil spring 34 to resiliently space the bed from the cabinet ends 11.

Fixed to the back side of the bed frame member 19, is an angle iron 35 as shown in detail in Fig. 7. Horizontally aligned therewith and set in the rear cabinet wall 13 is a cooperating angle iron 36, forming a wall abutment adapted to be engaged by the angle 35 to retain the bed frame in a stable horizontal position. This engagement together with the pivots serves as a

cantilever bed support. The bed is thereby stably fixed in open position by the overbalancing weight of the outer extending portion of the bed without other fastening or supporting means.

A stop 37 is fixed at the bottom 12 of the cabinet for engagement by the angle 35 on the bed frame to prevent pivotal rotation of the bed beyond a vertical or closed position. It will also be apparent that each of these stops 36, 37 and pivot 27 are suitably placed for cooperation, the exact position being determined by the weight and dimensions of the bed to give it firm cantilever support in the open position and overall balance in the closed position to allow easy rotation to and from open and closed positions.

A cabinet cover 15 is secured by hinges 38, shown in detail in Fig. 5 to the bottom edge of the outer side of the bed frame, when in open position. The cover is constructed of a flat plate or board surrounded by a reinforcing frame 40 at the edges, all inclosed in metal sheathing 41. The cover 15 forms a top of the cabinet in closed position and is folded back on the hinges, as shown in Fig. 4, to lie flat on the bottom 14 of the bed when in open position, and there held by any suitable clip (not shown).

Extending from end to end of the upper cabinet interior is a support 42 upon which is fixed a shelf 43 which extends and is attached to the rear wall 13 of the cabinet. This shelf serves as a support for the cover 15 when in closed position.

By means of hinges 44 secured to the support 42 a tiltably adjustable back rest 45 for the couch is secured. The back piece is formed of a metallic skin or sheathing 46 suitably braced by an inner framework of channel irons 47 extending from end to end of the back, bound into a rigid network by cross ribs 48. The face may be of any suitable covering material backed by conventional upholstery padding 49 which may be further resiliently supported by springs (not shown) or other conventional couch construction. Both ends of the back rest may be closed by metal sheathing 50.

Several plate brackets 51 are attached to the underside of the shelf 43 and are centrally bored with axially aligned holes to receive and rotatably support a shaft 52. Mounted on the shaft for rotary control thereof is a ring gear 53. A worm gear meshing with the ring gear 53 is fixed to a shaft 54 having a crank 55 for rotating the gears. Keyed or otherwise attached to the shaft 52 is an arm 56 which is suitably pinned to a link 57, the inner end of which is rigidly fastened through a bracket to the sofa back 46.

Thus it will be seen that the construction described provides a portable or stationary cabinet, or recessed wall or bulkhead wherein an easy folding bed-couch is mounted to fill the recess or cabinet in a neat substantially flush fit. For easy folding the bed is supported on a pair of aligned fixed pivots between the bed and stationary walls, placed off-center between the sides of the bed to form a stable cantilever support between the pivots and upper and lower stops cooperating with the inner side of the bed to hold it in a rigidly open position by the weight of the outer side of the bed acting in cantilever against the upper stop through the pivots.

In operation to open the bed, if a cabinet is used, the top 15 will be first swung open on hinges 38 and clipped to the bottom of the bed 14. The bed will then be pulled forward and will swing in an arc on pivots 24 until the channel 35 on

the bed frame 19 engages the stop 36 to stop the downward motion and retain the bed in horizontal position.

If the bed is to be used for sleeping, the sofa back 45 will be allowed to remain in its folded position, as shown in lower dotted lines of Fig. 4. If the bed is to be converted to a couch, the sofa back is adjusted to the position shown in Figs. 2 and 4 by manually rotating the crank 55, which acts through shafts 54 and 52, through worm and ring gears 53 and arm and link 56 and 57, attached to the sofa back. Through this mechanical linkage arrangement, the sofa back may be adjusted forward and backward to any comfortable position, or may be returned into the cabinet to make up the bed for sleeping or folding, or may be moved far upward and outward of the cabinet for cleaning or other purposes as shown in the upper dotted line position of Fig. 4.

In folded position it will be noted that the bed is retained by the lower stop 37 cooperating with the angle 35 on the side of the bed frame 19. In this position the sofa back is receded and the bed fits neatly thereover.

Thus is provided a simple, neat mechanical arrangement of a bed-couch operable easily without adjustment. It has no depending legs and no protruding braces or wall sockets; gives a flush wall fit; and has a clear space under the bed for easy cleaning or storage.

Various modifications will be suggested to one skilled in the art, for example the bed described can be made duplex as an upper and lower berth, and folding arm rests can be attached to the sofa back, it being intended that the specific description given above be merely exemplary of the invention and not limitative except as defined in the claims.

I claim:

1. A foldable bed-couch comprising upright supports having a bed frame and a couch back pivotally supported thereby, means cooperating with said bed pivotal means providing a cantilever support for said bed, and means to adjust the angle of suspension of the couch back into cooperative relationship with said bed to provide a side therefor and into cooperative relationship with said bed to utilize a portion of said bed as a seat in conjunction with said couch back.

2. A cabinet adapted to inclose and pivotally support a folding bed, a folding bed comprising a frame having an inclosing bottom and fixed pivots in opposite ends thereof positioned intermediate the longitudinal axis and the side of the bed nearest the back wall of the cabinet, supports for said pivots in opposite vertical ends of said cabinet, stop means fixed in said cabinet to stop the pivotal movement of the bed in vertical closed and horizontal open positions; one of said stop means and said pivots cooperating to form the sole bed support in open position, and the bottom of said bed cooperating with said cabinet to form the front wall thereof when the bed is pivoted into vertical closed position.

3. A cabinet adapted to inclose and support a folding bed, a bed comprising a frame having a bottom and fixed pivots in opposite ends intermediate the longitudinal axis and the side of the bed nearest the back of said cabinet, supports for said pivots in opposite vertical ends of said cabinet, stop means fixed in said cabinet to stop the bed in vertical closed and horizontal open positions, one of said stop means and said pivots cooperating to form the sole cantilever bed support in open position; the bottom of said bed in ver-

tical closed position cooperating with said cabinet to form a front wall therefor, and a cabinet top member pivotally fastened to the outer bottom edge of the bed and foldable over the side of the bed when in vertical closed position to form a top for said cabinet.
